FASTENING FOR RAILS

Jacob Rush Snyder, Cleveland, Ohio

Application June 26, 1946, Serial No. 679,516

8 Claims. (Cl. 238—349)

1

This invention relates to fastenings for railway rails and, more particularly, to a fastening of this kind in which the rail is yieldingly held against a support by a substantially rigid clamp subjected to spring pressure.

In rail fastenings of this kind a screw spike is usually employed as a connecting member and, during installation of the fastening, is driven into a tie so as to extend through the rigid clamp and the loading spring. The labor ordinarily employed in installing or servicing rail fastenings of this kind is not skilled labor and, unless precautions are taken, the screw spikes may be improperly driven so that in some cases they may not apply the desired load to the rail and, in other cases, they may be overdriven and cause excessive loading on the rail. The present invention overcomes this difficulty and provides an improved fastening which can be installed by unskilled labor and in which the screw spike will always be correctly driven so that all of the fastenings will be subjected to a desired substantially uniform loading.

As one of its objects the present invention aims to provide an improved fastening of this kind which can be formed by the use of a small number of parts adapted to be economically manufactured and installed.

Another object of the invention is to provide an improved construction for a fastening of the character mentioned in which the spring serves the dual purpose of applying the desired load to the clamp and acting as a gauge or stop for automatically determining the correct distance which the spike is to be driven into the tie.

A further object of this invention is to provide an improved construction for a rail fastening of this character in which the clamp has an inclined spring seat adapted to cooperate with the spring so as to enable the same to act as a gauge for the spike without preventing a desired yielding and rocking of the clamp to permit a limited amount of movement of the rail relative to the support.

The invention can be further briefly summarized as consisting in certain novel combinations and arrangements of parts hereinafter described and particularly set out in the appended claims.

In the accompanying sheet of drawings

Fig. 1 is a vertical sectional view taken through a tie plate and rail illustrating the improved fastening of the present invention.

Fig. 2 is a similar vertical sectional view taken

2

at a point such as to extend through the rigid clamp and the loading spring.

Fig. 3 is a partial plan view of the tie plate in detached relation and showing the shape of the tie plate opening.

Fig. 4 is a top plan view of the clamp showing the same in detached relation.

Fig. 5 is a bottom plan view thereof, and

Fig. 6 is an end view of the clamp as viewed from its inner or rail-engaging end.

As illustrated in the drawing, the invention provides a fastening in which a railway rail 10 is yieldingly held against a support which is here shown as comprising a tie plate 11 resting on a wooden tie 12. The rail 10 is shown as being of a conventional construction, which includes the usual head and web portions 10a and 10b, and a laterally extending base flange 13. The tie plate 11 is also shown as being of a conventional construction consisting of an elongated substantially flat metal plate having one or more upstanding ribs 14 extending thereacross in the direction of the axis of the rail 10 and forming a shoulder or shoulders adapted to be engaged by the edge or edges of the flange 13. The tie plate has suitably located openings 15 extending therethrough adjacent the rib, or ribs, 14. Each of the openings has a substantially circular portion 15a and, for a purpose to become more apparent hereinafter, each opening also has a slot portion 15b extending in a direction away from the rib 14.

The fastening also includes, as an important part thereof, a substantially rigid clamp 16 which is held against the tie plate and rail flange by means of a coiled spring 17 and a fastener in the form of a screw spike 18 extending through such clamp and spring. The clamp 16 is a one-piece metal body which can be economically manufactured and which, in this instance, is in the form of a forging having an opening 19 through which the screw spike 18 extends. At its outer end the clamp 16 is of substantial depth or height and has spaced bearing portions or pads 20 which engage the top surface of the tie plate 11 at points adjacent to, but on opposite sides of, the slot extension 15b of the tie plate opening. The outer end of the clamp also has a depending lug 21 located between the bearing portions 20 and which is engageable in the slot extension 15b.

The inner end of the clamp 16 is of relatively reduced height or thickness and overhangs the rail flange 13. This inner end is provided with a bearing portion or pad 22 which engages the upper surface of the rail flange 13.

adjacent the outer longitudinal edge thereof. The opening 19 of the clamp extends through the same between the outer and inner bearing portions 20 and 22 and is of a size to freely accommodate the unthreaded stem portion 18a of the screw spike 18. The intermediate portion of the clamp is recessed or arched upwardly on the underside thereof, as shown in the drawing, so as to extend in bridging relation over the shoulder 14 of the tie plate 11.

An important feature of the clamp 16 is the fact that this member is provided with a top bearing surface 23 which is inclined relative to the axis of the spike 18 and slopes downwardly and inwardly toward the rail flange 13. This top bearing surface forms a correspondingly inclined annular spring seat 24 extending around the opening 19 and against which the lower end of the coiled spring 17 bears. The top of the clamp is also provided with a pair of upstanding opposed ribs 25 which extend arcuately around the opening 19 and the spring seat 24, as shown in Fig. 4 of the drawing. These arcuate ribs form a positioning and retaining means for the lower end of the spring 17. The ribs 25 also serve to reinforce the clamp 16 and particularly the portions thereof which bridge the rib 14 of the tie plate and overhang the rail flange 13.

At the outer end of the clamp, the ribs 25 are of decreasing height and merge smoothly into the top bearing surface 23. At the inner end of the clamp, these ribs have portions 25a of increasing height and lateral thickness and reinforce this portion of the clamp as mentioned above. As shown in Fig. 4, these thickened inner ends 25a of the arcuate ribs 25 are spaced apart so that a portion of the downwardly and inwardly sloping bearing surface 23 is exposed therebetween to permit the free drainage of water, brine, or other corrosive liquid, from the top of the clamp, and in a direction away from the spike opening 19.

The screw spike 18 is provided with a head 18b having a clamping surface or shoulder 27 on the underside thereof which forms a seat for the upper end of the coiled spring 17. The stem of the spike is provided with a screw thread 28 which engages in the wooden tie 12, preferably in a preformed opening thereof. The coiled spring 17 is disposed around the unthreaded stem portion 18a of the spike so as to extend between the spring seat 24a and the clamp 16 and the spring seat 27 on the underside of the head of the spike. The spring 17, in its free state has substantially the shape of a right circular cylinder, and has dimensions and characteristics suitable for applying a desired load to the clamp 16 for yieldingly holding the rail flange 13 against the tie plate 11 and the tie plate against the wooden tie 12. The unthreaded stem portion 18a of the spike is also of appropriate length in relation to the length of the spring 17, the height or thickness of the clamp 16 and the thickness of the tie plate 11.

In installing the fastening herein disclosed, the screw spike 18 is driven into the tie 12 so as to subject the spring 17 to compression against the inclined spring seat of the clamp 16. During this operation the spike is driven into the tie until the convolutions of the spring are compressed to a solid or closed condition on the side of the spring which is remote from the rail and located above the outer bearing portions 20. When the convolutions of the spring have

been solidly compressed at the outer side, as shown in Fig. 1 and 2, the spring will serve as a gauge or stop for automatically determining and limiting the extent to which the screw spike is to be driven into the tie for obtaining a correct loading of the rail.

By reason of the inclination of the spring seat 24, the spring convolutions will not be compressed to such a closed or solid condition on the side of the spring adjacent the rail 10 but will remain spaced apart as shown in Figs. 1 and 2 of the drawing. This spacing of the convolutions on the inner side of the spring will permit the inner end of the clamp 16 to move upwardly and downwardly relative to the spike 18 in accordance with rising and falling movements of the rail 10 during the passage of trains thereover. This movement of the clamp takes place as a rocking movement relative to the tie plate 11 during which the outer end of the clamp fulcrums on the bearing portions 20 and is held against lateral shifting relative to the tie plate by the engagement of the depending lug 21 in the slot extension 15b of the tie plate opening. The engagement of this lug in the slot 15b also prevents the inner surface of the clamp opening 19 from having an abrading or scraping action on the unthreaded stem portion 18a of the spike. Additionally, this depending lug 21 serves the important purpose of holding the clamp in its proper position and prevents the same from rotating about the spike.

Although the convolutions of the spring 17 are compressed to a solid condition at the outer side of the spring during the driving of the screw spike, as explained above, this condition usually obtains or exists only during the installation of the fastening because as soon as a few trains have passed over the rail 10 some settling of the tie plate 11 into the wooden tie 12 will take place and will result in the closed convolutions of the spring being released or spread apart to some extent. It might well also be explained at this point that the driving of the screw spike 18 into the tie can be accomplished by the use of any suitable tool. This operation is preferably carried out with a wrench of the type having an automatic torque overload release so that when the spike has been driven inwardly to the point at which the spring convolutions are compressed to the solid condition explained above, the release mechanism of the wrench will yield and will prevent the spike from being subjected to a torsional load greater than that needed for compressing the spring to the solid condition.

Reverting to the inclined spring seat 24 provided by the top bearing surface of the clamp 16, it will be observed that the spring seat thus provided has high and low points 24a and 24b located at substantially opposite sides of the opening 19. These high and low points are here shown as being continuous portions of the spring seat 24 although they could be formed on the clamp in various other ways. These high and low points or seat portions cooperate with the spring 17 so as to enable the convolutions at the outer side of the spring to act as a gauge for the driving of the spike, as explained above, and for the loading of the spring to provide a desired predetermined pressure on the rail flange. The inclination here shown for the top bearing surface 23 of the clamp in providing these high and low points is approximately seven degrees, although this value is not critical and can be in-

creased or decreased in accordance with different existing conditions and characteristics.

When rail fastenings embodying the above described constructions have been installed, they possess numerous important advantages over rail fastenings heretofore provided and some of these advantages have already been pointed out above. Certain other important advantages of the improved fastening can well be explained at this point. The compression of the spring 17 to the above described closed condition of its convolutions at the remote side thereof, subjects the outer end of the clamp to an increased load and this is an advantage because it reacts against the head of the spike 18 in a manner to prevent the spike from being oscillated or deflected during rising and falling movements of the rail 10 and which might otherwise result in springing or breakage of the spike or in elongation of the spike-hole in the wooden tie. Another important advantage of the improved fastening is that the automatic gauging of the extent to which the spike is to be driven into the tie and which is accomplished as above explained, results in the same predetermined load being uniformly applied to the rail for each of the fastenings thus installed.

Although the improved rail fastening of the present invention has been illustrated and described herein in considerable detail, it will be understood, of course, that the invention is intended to include all changes and modifications coming within the scope of the appended claims.

Having thus described my invention, I claim

1. In a rail fastening of the character described, a support, a rail having a base flange resting on said support, a substantially rigid clamp having an outer end bearing portion rockably engaging said support and an inner end bearing portion engaging the top of said base flange, said clamp also having an opening therethrough between said end bearing portions and an inclined spring seat surrounding said opening, a connecting member connected with said support so as to extend through the clamp opening and having holding means spaced above said inclined spring seat, and a coiled spring surrounding said connecting member and compressed against said inclined spring seat by said holding means, the inclination of said spring seat being such that it slopes downwardly and inwardly toward said base flange and the compression of said spring being such that it is under greater compression at the outer side of the clamp than it is at the inner side of the clamp.

2. In a rail fastening of the character described, a support, a rail having a base flange resting on said support, a substantially rigid clamp having an outer end bearing portion rockably engaging said support and an inner end bearing portion engaging the top of said base flange, said clamp also having an opening therethrough between said end bearing portions and a spring seat on the top thereof comprising relatively high and low seat portions located on the same sides of the clamp opening as said outer and inner end bearing portions respectively, a connecting member connected with said support so as to extend through the clamp opening and having holding means spaced from said spring seat, and a coiled spring having in its free state substantially the shape of a right circular cylinder surrounding said connecting member and subjected to compression with one end engaging said holding means and its other end engaging

said high and low seat portions, said spring being subjected to greater deflection on the side corresponding with said high seat portion than on the side corresponding with said low seat portion.

3. In a rail fastening of the character described, a support, a rail having a base flange resting on said support, a substantially rigid clamp having an outer end bearing portion rockably engaging said support and an inner end bearing portion engaging the top of said base flange, said clamp also having an opening therethrough between said end bearing portions and an inclined spring seat surrounding said opening, a connecting member connected with said support so as to extend through the clamp opening and having holding means spaced above said inclined spring seat, a coiled spring surrounding said connecting member and compressed against said inclined spring seat by said holding means, and upstanding ribs on said clamp and extending in arcuate relation around said spring seat, the inclination of said spring seat being such that it slopes downwardly and inwardly toward said base flange and the compression of said spring being such that it is under greater compression at the outer side of the clamp than it is at the inner side of the clamp.

4. In a rail fastening of the character described, a support, a rail having a base flange resting on said support, a substantially rigid clamp having a relatively thick outer end portion rockably engaging said support and an inner end portion of relatively reduced thickness overhanging the rail flange and engaging the top thereof, said clamp also having an opening therethrough between said end portions and a spring seat surrounding said opening and inclined downwardly and inwardly toward the rail flange and extended onto said inner end portion, a connecting member connected with said support so as to extend through the clamp opening and having holding means spaced from the inclined spring seat, a coiled spring surrounding said connecting member and compressed against said inclined spring seat by said holding means, and upstanding ribs on said clamp and extending arcuately around said spring seat, said ribs having spaced apart end portions of increased thickness formed integral with said inner end portion.

5. In a rail fastening, a tie, a tie plate on said tie, a rail having a base flange supported on said tie plate, said tie plate having a rail-gauging shoulder thereon and an opening therethrough adjacent said shoulder, a clamp bridging said shoulder and having end bearing portions adapted to bear respectively on the rail flange and tie plate and also having an opening therethrough between said end bearing portions, a fastener having a stem extending into the tie 60 through the openings of said tie plate and clamp and also having a holding portion spaced above the clamp, said clamp having a top bearing surface surrounding the opening thereof and which is inclined relative to the axis of said fastener 65 so as to slope downwardly and inwardly toward said base flange, and a spring surrounding the fastener and subjected to compression between said holding portion and said top bearing surface, said spring serving to yieldingly hold said clamp against the rail flange and tie plate and the inclination of said top bearing surface enabling the spring to also serve as a gauge for limiting the extent to which the fastener is driven into the tie.

6. In a rail fastening, a tie, a tie plate on said

tie, a rail having a base flange supported on said tie plate, said tie plate having a rail-gauging shoulder thereon and an opening therethrough adjacent said shoulder, a clamp bridging said shoulder and having end bearing portions adapted to bear respectively on the rail flange and tie plate and also having an opening therethrough between said end bearing portions, a fastener having a stem extending into the tie through the openings of said tie plate and clamp and also having a holding portion spaced above the clamp, said clamp having a top bearing surface surrounding the opening thereof and which has high and low portions located on the outer and inner sides respectively of the opening of the clamp so as to slope downwardly and inwardly toward said base flange, and a coiled spring surrounding the fastener and subjected to compression between said holding portion and said top bearing surface for yieldingly holding the clamp against the rail flange and tie plate, said spring being adapted to be solidly clamped at one side only thereof between said holding portion of the fastener and said high portion of the clamp for limiting the extent to which the fastener is initially driven into the tie.

7. In a rail fastening, a tie, a tie plate on said tie, a rail having a base flange supported on said tie plate, said tie plate having a rail-gauging shoulder thereon and also having an opening therethrough adjacent said shoulder and including a slot portion extending in a direction away from the shoulder, a substantially rigid clamp bridging said shoulder and having inner and outer end bearing portions adapted to bear on the rail flange and tie plate respectively and also having an opening therethrough between said end bearing portions and a depending lug engageable in said slot portion of the tie plate opening, a headed fastener having a stem extending into said tie and extending through the openings of the tie plate and clamp, said clamp having a top bearing surface which is inclined relative to the axis of said fastener so as to slope downwardly and inwardly toward said base flange, and a coiled spring surrounding said fastener and subjected to compression between said top bearing surface and the head of the fastener for yieldingly holding the clamp against said rail flange and tie plate, the compression of said spring being such that the convolutions thereof remain spaced apart on the side thereof nearest the rail so as to permit rocking of the

clamp on its outer end bearing portion, said spring also serving as a gauge for limiting the extent to which the fastener is initially driven into the tie.

- 5 8. In a rail fastening, a tie, a tie plate on said tie, a rail having a base flange supported on said tie plate, said tie plate having a rail-gauging shoulder thereon and also having an opening therethrough adjacent said shoulder and including 10 a slot portion extending in a direction away from the shoulder, a substantially rigid clamp bridging said shoulder and having inner and outer end bearing portions adapted to bear on the rail flange and tie plate respectively and also having an opening therethrough between said end bearing portions and a depending lug engageable in said slot portion of the tie plate opening, a headed fastener having a stem extending into said tie and extending through the openings of 15 the tie plate and clamp, said clamp having a top bearing surface which is inclined relative to the axis of said fastener so as to have high and low portions located respectively on the same sides of the clamp opening as said outer and inner end bearing portions, and a coiled spring surrounding said fastener and subjected to compression between said top bearing surface and the head of the fastener for yieldingly holding the clamp against said rail flange and tie plate, said spring being adapted to have its convolutions at one side thereof compressed to a substantially solid condition between the head of the fastener and the high portion of said top bearing surface for limiting the extent to which the fastener is 20 initially driven into the tie while its convolutions at the other side thereof remain spaced apart so as to permit rocking of the clamp on its outer end bearing portion.
